ELECTRIC SWITCH, PARTICULARLY FOR
USE IN CONTROL OF RAILWAY SIGNALSAndrew Brown, Roland Harris Dunn, and David
Gordon McKie, London, England, assignors to
International Standard Electric Corporation,
New York, N. Y.Application September 16, 1936, Serial No. 101,028
In Great Britain September 27, 1935

9 Claims. (Cl. 200—153)

This invention relates to electric switches having parts moved by different means and adapted to close (or open) an electric circuit when the parts so moved are in given relative 5 positions.

One feature of this invention consists in an electric switch of the kind referred to comprising a part movable by one means, a second part movable by a second means, a third part movable by both the first and second means, and means for closing (or opening) an electric circuit when contacts on all three parts are in a given relative position.

Another feature of the invention consists in an 15 electric switch of the kind referred to comprising a first disc carrying contacts and rotatable directly by one means, a brush rotatable directly by a second means over said contacts and also over contacts on a second disc for completing 20 an electric circuit, and means for rotating said second disc by said first and second means in step down ratios that are complementary to one another.

Yet another feature of the invention consists 25 in an electric switch of the kind referred to for controlling an electric circuit according to the relation between two different series of impulses comprising ratchet wheels adapted to be stepped by the respective series of impulses, inner and 30 outer sun wheels attached to said ratchet wheels, a disc carrying contacts in said circuit attached to one of said sun wheels, a disc carrying other contacts in said circuit attached to a planet wheel meshing with each of said sun wheels, and 35 a disc carrying a brush adapted to bridge said contacts to complete said circuit and attached to the other of said sun wheels.

One application of the invention is to switches 40 used for counting the wheels of a train into and out of a given section of track. The signals are automatically set to danger when the first wheel enters the section, and by means of treads operated by the passage of the wheels, or by other 45 means, an impulse is sent to control equipment for the signals for each wheel entering the track section and another impulse for each wheel leaving the section. When the same number of out- 50 counting as in-counting impulses has been received a circuit is completed for a relay which restores the signals to clear or allows them to be manually restored. For such application the switch of the present invention possesses many advantages. It allows of a large total count before the in-counting portion reaches initial posi-

tion again, and it allows in-counting and out-counting to take place simultaneously.

One embodiment of the invention will be described with reference to the accompanying drawing but it is to be understood that the invention is not restricted to that embodiment, nor to a switch intended for this particular application.

Figure 1 of the drawing shows a side view of the switch, half in cross section, whilst 10 Figures 2 to 6 illustrate details thereof.

Referring to the drawing a ratchet wheel 2 and an insulating fibre disc 3 are fixed to a central shaft 4, journaled in a suitable frame (not shown). The inner sun wheel 4 of a sun and 15 planet gear is secured to the ratchet wheel 2. Planet wheels, of which one only (5) is shown, are rotatably mounted on a spider 6 and engage with the sun wheel 4 and with an outer sun wheel 7. The spider 6 is mounted on a sleeve 8 20 freely rotatable on the shaft 4. The sleeve 8 carries a second insulating fibre disc 9. The outer sun wheel 7 is fixed to an outer sleeve 10 freely rotatable on sleeve 8 and carrying a ratchet wheel 11 and an insulating fibre disc 12, 25 which latter carries a double brush 13 (Figs. 1 and 2) wiping over the peripheries of the discs 3 and 9. One terminal of the circuit being controlled is connected to a brush (not shown) wiping on a metal annulus 14 fixed to the insulating fibre disc 12 on the opposite side from that to which the brush 13 is fixed. The annulus 14 is cut away as shown in Fig. 3 in order to be clear of the rivets fastening brush 13 to disc 12. Another brush 19 (Fig. 2) is fixed on the side of the disc 12 opposite to that on which the annulus 14 is fixed, but connected to the annulus by studs passing through the fibre. Brush 19 wipes on a metal plate 15 (Fig. 4) fixed to the insulated fibre disc 9. The circuit terminal is thus effectively connected to the plate 15. The edge of this plate is within that of the fibre disc except for a projection 20 where it is level therewith. The projection 20 extends over sufficient distance for the brush 13 to contact with it at the initial 45 position and for the distance through which disc 9 is moved by two steps of either of the ratchet wheels 2 or 11 to each side of the home position. On one side of the disc 3 which is also of insulated fibre is mounted a metal plate 16 Fig. 6 50 which has two projections 21 and 22 level with the fibre each two steps removed from home position, and is connected by metal studs passing through the fibre to a metal annulus 17 (see Fig. 5) on the other side of the disc 3. A metal an-

nulus 18 surrounding, but separated from the annulus 17 has a projection 23 level with the fibre disc 3 at the home position. Circuit terminals are connected to brushes 24 and 25 wiping over the annuli 17 and 18 respectively.

In operation, the switch is arranged originally in the home position in which the brush 13 rests on the projections 23 and 20 and so completes a circuit between the plate 15 and annulus 18. The relay responding to incounting impulses operates a pawl stepping one of the ratchet wheels and the relay responding to out-counting impulses operates a pawl stepping the other ratchet wheel in well known manner. It is immaterial which ratchet wheel is rotated by in-counting impulses but for simplicity of description it will be assumed that this is the ratchet wheel 2. On the first in-counting impulse ratchet wheel 2 is rotated through the distance of one tooth. Disc 3 is rotated directly, an equivalent amount, and disc 9 is rotated through the sun wheel 4 and planet wheel 5 by a lesser distance. The first impulse is sufficient to break the circuit completed in the home position between annulus 18 and plate 15. Further in-counting impulses continue to rotate the discs 3 and 9 and on the completion of two steps a circuit is completed between the plate 15 and plate 17. After another step this circuit is broken, and both circuits continue to be broken during further in-counting impulses. The number of revolutions of disc 3 before both discs 3 and 9 are back in initial relative positions depends on the relative diameters and numbers of teeth on the sun wheel 4 and planet wheel 5. In order to meet railway requirements that a total number of 599 wheels can be counted, it has been found satisfactory to provide 60 teeth on the sun wheel 4 and 12 teeth on the planet wheel 5, the diameters being in the same ratio. Then twelve complete revolutions of the ratchet wheel 2 are necessary before the discs 3 and 9 return to the same relative positions. There are 50 teeth on ratchet wheel 2 and therefore 600 steps are made before this occurs. There are 84 teeth on the sun wheel 7 and the diameter of this wheel is in corresponding ratio. When ratchet wheel 11, which is provided with the same number of teeth as ratchet wheel 2, is stepped during the out-counting (in the same direction as ratchet wheel 2) the brushes 13 and sun wheel 7 are rotated correspondingly, whilst the disc 9 is rotated through the sun and planet gearing in a ratio complementary to that by which it was rotated by ratchet wheel 2. The circuits are again closed when the discs 3 and 9 and brushes 13 are again in the same relative positions and this occurs when the number of out-counting impulses is the same as those by which ratchet 2 was previously stepped. It is clear, however, that in-counting and out-counting may take place simultaneously.

It is to be understood that the invention is not limited to the precise details shown and described. For example, other gear ratios might be used for counting up to the same total number or up to other different totals.

For use in other applications than that specifically referred to the projections on which brush 13 makes contact could be arranged to close a circuit when the discs are a given number of

steps apart. It is also clear that the projections and depressions could be interchanged so as to make an electric circuit in all positions but the desired one or few. It is also clear that, as regards certain features of the invention, the two sun wheels could be driven continuously instead of step by step.

What is claimed is:

1. An electric switch of the kind referred to comprising a contact part movable by one means, a second contact part movable by a second means, a third contact part movable by both the first and second means and means for closing (or opening) an electric circuit when contacts on all three parts are in a predetermined relative position. 15

2. An electric switch as claimed in claim 1 in which the three movable parts are rotatable discs.

3. An electric switch as claimed in claim 1 in which the said first and second means cause 20 movements of the said third part in a ratio different from those in which they respectively cause the movements of the first and second parts.

4. An electric switch of the kind referred to 25 comprising a first disc carrying contacts and rotatable directly by one means, a brush rotatable directly by a second means over said contacts and also over contacts on a second disc for completing an electric circuit and means for rotating 30 said second disc by said first and second means in step down ratios that are complementary to one another.

5. An electric switch as claimed in claim 4 in 35 which said first and second discs are attached to inner and outer sun wheels of a sun and planet gearing driven by said first and second means and said third disc is driven by a planet wheel meshing with said inner and outer sun wheels.

6. An electric switch as claimed in claim 4 in 40 which each of said sun wheels is driven in a step by step manner by means of a pawl acting on a ratchet wheel attached thereto.

7. An electric switch of the kind referred to 45 for controlling an electric circuit according to the relation between two different series of impulses comprising ratchet wheels adapted to be stepped by the respective series of impulses, inner and outer sun wheels attached to said ratchet wheels, a disc carrying contacts in said circuit attached 50 to one of said sun wheels, a disc carrying other contacts in said circuit attached to a planet wheel meshing with each of said sun wheels, and a disc carrying a brush adapted to bridge said contacts to complete said circuit and attached to 55 the other of said sun wheels.

8. An electric switch as claimed in claim 7 in 60 which the said sun wheels are rotated in the same direction.

9. An electric switch as claimed in claim 7 in 65 which the inner one of said sun wheels and the disc attached thereto is mounted on a shaft, the said planet wheel is mounted on a spider carried on a first sleeve rotatable on said shaft and the outer of said sun wheels and the disc carrying the brush are mounted on a second sleeve rotatable on said first sleeve.
